ILLINOIS, ASSIGNEES TO CRIBBEN & SEXTON COMPANY, OF CHICAGO, ILLINOIS,
A CORPORATION OF ILLINOIS.

COMBINED COAL AND GAS RANGE.

1,251,153.

Specification of Letters Patent. Patented Dec. 25, 1917.

Application filed March 30, 1916. Serial No. 87,668.

To all whom it may concern:

Be it known that we, GEORGE D. WILKINSON and AUGUSTUS F. HARTER, citizens of the United States, residing, respectively, at 5 Oak Park and Chicago, county of Cook, State of Illinois, have invented a certain new and useful Improvement in Combined Coal and Gas Ranges, and declare the following to be a full, clear, and exact description of the same, such as will enable others skilled in the art to which it pertains to make and use the same, reference being had to the accompanying drawings, which form a part of this specification.

15 The primary object of our invention is to produce gas-burning oven attachments for an ordinary coal range or to make a combined coal and gas range which will require no parts to be removed or placed in position 20 when changing from gaseous fuel to solid or vice versa.

A further object of our invention is to produce a combined coal and gas range which will operate as efficiently on solid 25 fuel as do the best types of coal ranges and which will also operate efficiently when burning gas.

30 A further object of our invention is to produce a simple and novel gas-burning attachment for the oven of a coal range which will permit the range to be transformed into a gas-burning apparatus by the mere act of turning on the gas and to be converted into a simple coal-burning apparatus by the mere 35 act of shutting off the gas.

40 A further object of our invention is to produce a simple and novel gas-burning heating means for an oven which will cause the inlet for air and the outlet for combustion gases to be regulated automatically in accordance with the amount of fuel which is being consumed.

45 A further object of our invention is to produce a simple and novel flame spreader for an oven heating burner which will serve also as one of the usual trays or supports found in the ordinary coal range.

50 The various features of novelty whereby our invention is characterized will hereinafter be pointed out with particularity in the claims; but, for a full understanding of our invention and of its objects and advantages, reference may be had to the following de-

tailed description taken in connection with the accompanying drawings, wherein:

55 Figure 1 is a front elevation of a coal range equipped in accordance with the present invention, portions being broken away to expose parts which would otherwise be concealed;

60 Fig. 2 is a section taken approximately on line 2—2 of Fig. 1;

65 Fig. 3 is an end view of the range looking toward the left from the right hand end of Fig. 1; and

Fig. 4 is a rear view of the range.

70 Referring to the drawings, 1 represents the oven of a coal range of any usual or suitable construction, below which is the usual flue or passage, 2, through which the hot combustion gases from the coal fire pass, and behind which is the usual vertical outlet flue, 3.

75 In accordance with one feature of our invention we place a burner, 4, at about the middle of the bottom of the oven, providing for this purpose an open ended chamber, 5, extending through the bottom wall of the oven, through the draft passage, 2, and through the bottom wall of the draft passage; the chamber, 5, being bounded by a suitable shell or wall, 6, which shuts off communication with the draft passage 2. The burner is supplied with fuel through a suitable pipe, 7, fixed in any suitable way on 85 the under side of the bottom wall of the range.

90 In order that the oven may appear just like an ordinary oven in a coal range, while coal is being burned, and avoid loss of efficiency, we construct the burner in such a way that it may be raised and lowered the burner seating itself in the chamber, 5, and completely closing the top thereof so that the bottom wall of the oven remain continuous and unobstructed, when the oven is being heated by burning coal, this arrangement being illustrated in Fig. 1; and the burner being raised up so as to project somewhat above the bottom wall of the oven, as 100 indicated in Fig. 2, when the oven is to be heated by burning gas; the parts being so shaped that when the burner is raised an air passage is formed around the same so that air to support combustion may be 105 drawn up through the chamber 5. To se-

cure the best results we prefer to make the top of the burner flat and imperforate, the discharge orifices, 8, extending radially out of the same at a short distance below the plane of the top surface so that when the burner is seated the orifices will be covered.

For the sake of simplicity and durability we prefer to have the supply pipe or conduit, 7, stationary, the inner end, 9, being bent 10 upwardly at the axis of the chamber 5 and extending into a downwardly projecting tubular neck, 10, on the burner in which it has a comfortable sliding fit. With this arrangement only the burner need be raised 15 and lowered. For the purpose of controlling the position of the burner we have provided a lever, 11, which is pivoted between its ends on the under side of the range as at 12, so as to swing about a horizontal axis; the supporting means for the lever being preferably 20 a boss, 13, on the side of the supply pipe 7 which permits the lever to be mounted on its support before being placed in position under the range. The inner end of the lever, 25 as indicated at 14, embraces or surrounds the upwardly projecting part, 9, of the supply pipe and engages with the under edge of the sleeve or hub portion, 10, of the burner. By oscillating the lever, the burner may be 30 caused to rise to its working position or be permitted to seat itself in its idle position. The outer end of the lever, as well as the outer end of the supply pipe 7 projects into or through an opening, 15, in the base, 16, 35 upon which the range proper is supported. The outer end of the pipe, 7, is provided with the usual valved air opening, 17, into which projects a nozzle or nipple, 18, on the lower end of a vertically arranged gas pipe, 40 19. The pipe 19 contains a valve, 20, from which extends a valve stem, 21, which passes through a plate, 22, at the front of the range and is there provided with an operating handle, 23, and with a suitable pointer, 24, 45 swinging between suitable stationary pins or stops, 25. When the pointer is against one of the stops the valve is fully closed and when it is against the other stop the valve is fully open.

50 We provide the valve stem with a laterally projecting arm, 26, and to this arm we connect the upper end of a rod or link, 27, the lower end of which is connected to the outer end of the lever 11. The result is that whenever the handle, 23, is turned to operate the valve, it also produces a movement of the burner, causing the burner to rise from its seat when the gas is turned on and to approach its seat and finally seat itself as the 55 gas is turned off.

Since the products of combustion from the burner are discharged into the oven some means must be provided to carry them away and, to this end, we have placed in the top 60 of the oven a shallow flue, 30, opening at its

rear end into the main flue, 3, and provided with inlet openings, 31, in the front end which is near the front end of the oven. When the range is being used as a coal range 70 communication between the interior of the oven and the main flue, 3, should of course be interrupted and we have therefore provided a damper, 32, for controlling communication between the rear end of the flue 30 and the flue 3. The damper is fixed upon the inner end of a horizontal rock shaft, 33, which projects out through the side wall of the flue 3 to the end or side of the range where it is provided with a crank, 34. Since it is desirable that the damper 32 be closed 75 whenever the gas is shut off and the burner lowered, it is possible to secure the control of the valve, the burner and the damper from the single controlling handle by simply providing a suitable connection between the 80 damper shaft, 33, and the valve stem, 21. In the arrangement illustrated, we have mounted on the end of the range a lever, 35, having at one end a fork or jaw, 36, engaging the crank 34, on the damper shaft; the 85 other end of the lever being connected to the arm 26 on the valve stem by means of a link or rod, 36. The result is that whenever the operating handle, 23, is turned, the controlling valve, the burner and the damper are shifted in unison so that the range is converted from a coal range to a gas range 90 or vice versa by the mere act of turning a simple controlling handle. Still another advantageous result is obtained and that is 95 that the proper proportion is always maintained between the fuel, the air inlet and the outlet for the combustion gases, no matter whether the valve is wide open or only partially open.

In using a burner in the bottom of an oven, it is necessary, in order to spread the heat, to employ some sort of a spreading means and therefore, in order to avoid the use of parts which must be removed when the range 100 is being used as a coal range, we have provided a plate, 40, which takes the place of one of the usual trays or detachable shelves that are employed in ovens; this plate being preferably imperforate throughout the main 115 central portion and being cut away more or less in the vicinity of the four edges so that when it is placed in its lowermost position as illustrated in Figs. 1 and 2 of the drawings, it lies just above the burner when the latter 120 is raised, spreading the flame and causing the products of combustion to travel to the four vertical walls of the oven before they rise into the main body of the oven. On the under side of the plate, 40, we place a small 125 open ended tunnel, 41, the rear end of which extends into proximity to the burner while the front end extends into proximity to the front end of the stove. When the oven door, 42, is opened, the front end of the tunnel is 130

exposed and when the gas is turned on some of it flows out through the tunnel and may be ignited by a lighted match held at the outer end.

5 When it is desired to place a pan in which something is being cooked or baked on the bottom wall of the oven the plate, 40, is simply shifted to a higher position, out of the way, just as is done in the case of the 10 ordinary tray or pan. When the plate is in one of its upper working positions, it will serve to support a pan in the top of the oven so that baking or cooking can progress both in the lower half and the upper half 15 of the oven.

Another feature to which we have not heretofore referred but which is probably self evident, is that any suitable means may be desired for holding the valve stem and 20 parts connected therewith in either extreme position or in any intermediate position. In the arrangement shown this device takes the form of a flat spring, 50, secured on the rear side of the bracket or plate 22 and pressing 25 against the valve stem. Any other suitable means may of course be employed.

While we have illustrated and described with particularity a single specific construction embodying the various features of our 30 invention, we do not desire to be limited to the exact details so illustrated and described; but intend to cover all forms and arrangements which come within the definitions of our invention constituting the 35 pended claims.

We claim:

1. In a combined coal and gas range, an oven provided with an opening extending through one wall thereof and placing the 40 interior of the oven in communication with the outside atmosphere, the oven having an outlet for combustion gases, a burner movably arranged in said opening and serving as a controlling valve therefor, a damper for 45 said outlet, and means for shifting the burner and the damper in unison with each other to maintain the proper relation between the air inlet and the outlet for the combustion gases.

50 2. In a combined coal and gas range, an oven having an opening through the bottom thereof and a discharge outlet for combustion gases, a burner arranged within said opening in the bottom of the oven 55 and movable from a position in which it

closes the opening and has its upper surface flush with the top of the bottom wall of the oven to a position in which a portion of the burner projects into the oven, a damper for the said discharge outlet, and 60 means for simultaneously shifting said burner and said damper.

3. In a combined coal and gas range, an oven having an opening through the bottom thereof and a discharge outlet for combustion gases, a burner arranged within said opening in the bottom of the oven and movable from a position in which it closes the opening and has its upper surface flush with the top of the bottom wall of the oven 65 to a position in which a portion of the burner projects into the oven, a damper for the said discharge outlet, a fuel valve; and means for simultaneously adjusting the valve, the damper and the burner. 75

4. In a combined coal and gas range, an oven having an air inlet opening extending through one wall thereof, a burner having a part cooperating with said opening to serve as a valve therefor, a device for controlling the supply of fuel to the burner, and means for simultaneously shifting said device and said burner to control the flow of fuel and vary the effective area of said air inlet opening according to the amount of 80 fuel which is being delivered.

5. In a combined coal and gas range, an oven having an opening through the bottom thereof, a gas conduit arranged underneath the oven and having its inner end projecting into said opening, a combined burner and valve for said opening having its inlet end arranged to slide vertically on the adjacent end of said conduit, an actuating lever for said combined burner and valve, a fuel 95 valve, and means for simultaneously actuating said fuel valve and said lever. 90

6. In a combined coal and gas range, an oven having an opening through the bottom thereof, a combined burner and valve in said 100 opening, and means for supporting said burner and valve in a position wherein it closes said opening or in any one of a plurality of positions in each of which the burner and valve extends upwardly into the 105 oven.

In testimony whereof we sign this specification.

GEORGE D. WILKINSON.
AUGUSTUS F. HARTER.
